STRUCTURAL UNIT

Chester J. O'Brien, Chicago, Ill.

Application February 15, 1937, Serial No. 125,768

6 Claims. (Cl. 72—61)

This invention relates in general to a reinforcing structural unit for beams, joists, and the like, and has more particular reference to a reinforcing unit of this kind in which the stirrup elements or some of them are provided with integral supporting legs or form spacing units.

An important object of the invention is in the provision of a concrete reinforcing structural unit for joists, beams, and the like, adapted to reinforce the beams against the various strains to which they are subjected.

A further object of the invention is in the provision of an improved structural unit for reinforcing concrete beams which comprises a combined chair and stirrup having means for spacing them in a form to which they are applied.

A still further object of the invention is to produce a structural unit of this kind which will form the necessary chairs, stirrups and spacers with a minimum number of parts.

Other objects of the invention will appear hereinafter, the accompanying drawing illustrating preferred embodiments of the invention in which,

Fig. 1 is a perspective view of one of the units; Fig. 2 is a sectional view showing a unit cast in place in a concrete form;

Fig. 3 is a perspective view of a stirrup;

Fig. 4 is a perspective of a combined stirrup and spacer forming element; and

Fig. 5 is a perspective view of a modification.

In applying a structural unit composed of metal bars or rods to the forms for casting a concrete beam or joist it is desirable that the units be supported in spaced relation to the outer faces of the beams and that they may be positioned and held in place against dislodgement while the concrete is being poured and as it becomes set.

A further desirable feature of structural units is to provide supporting legs which are strong, rigidly attached, and are not likely to become bent or broken. In the present invention these objects are accomplished by making the elements of a simple form so that they can be combined to provide a stirrup with projecting supporting legs forming a material and easily attached structural part thereof.

Referring now more particularly to the drawing, this improved structural unit comprises a plurality of unitary stirrup elements 10, each of which is substantially U-shaped, having outwardly bent extremities 11. These stirrup elements are rigidly attached and secured together in upwardly spaced relation by means of longitudinally

extending rods 12, 13, 14 and 15 which are located at the tops and bottoms of the U-shaped sides and in the angle of the lateral extensions 11 adjacent the tops thereof.

These bars and elements 10 are usually attached together by welding, either electrically or in any other suitable manner, so that they present a fixed rigid structure which is adapted to be set in place in the formation of a concrete beam, joist, and the like.

In the structural unit, at either end, or intermediate the unitary structural elements 10 are supporting and spacing elements, each comprising a pair of substantially Z-shaped bar members 16 having an extremity 17 at one end corresponding to the bent extremities 11 of the unitary elements 10 and having an angularly bent portion 18 at the other end, and an outwardly or downwardly turned leg at the extremity of this portion. Two of these members 16 are placed oppositely so that their extremities 17 will be parallel to the extremities 11 of an element 10 and the bottom portions 18 will be placed together with the legs 19 at the opposite sides of the lower end of the structural element thus formed, the portions 18 being rigidly and permanently attached to each other by welding or securing them at spaced spots or along their contacting edges so that when thus attached they are of substantially the same shape as the unitary elements 10 with the exception that they have supporting legs 19 projecting at each side of the lower end thereof.

When these elements 10 and 16 are combined and attached in spaced relation by the rods 12, 13, 14 and 15 as shown in Fig. 1, the unit is complete for incorporating it in a concrete structure.

A concrete receiving form is made usually of boards 20, 21, and 22 to constitute a beam at the lower side of a floor and a mass of concrete 23 is poured in the form and allowed to set and harden. Before the concrete is poured into the form a structural unit as shown in Fig. 1 is inserted from the top into the form and if of the proper dimensions the legs 19 will extend into the corners or angles at the bottom of the form, thereby spacing it properly from the bottom and sides of the form so that only the extremities of the legs can possibly be visible in the completed beam structure which will be left when the forms are removed.

A similar structure is shown in Fig. 5 except that the structural elements 10' and 16' have extremities 11' and 17' along one side which are turned inwardly.

In actual practice these reinforcing units are made in different or substantial lengths and may be cut off as desired for shorter lengths.

Instead of the feet 19 extending into the angles of the form as shown in Fig. 2 they may simply extend downwardly and contact with the lower form board, as 22, or they may extend outwardly parallel with the bottom portion 18 to engage the outer sides of an inclined beam as shown in Fig. 2. Structural units made up in this manner are advantageous and desirable because the stirrup elements are so supported, spaced and positioned that nothing is left to the skill or attention of a workman in placing the structural units in the forms. The reinforcing bars hold the elements in proper spaced relation, the supporting feet or legs properly space the bars and also the elements from the sides of a form and prevent any portion of the structural unit from resting against the side of the form to be visible in the concrete beam when the form is removed. These structural units are also inexpensive for production and may be conveniently and easily handled in actual use.

25 I claim:

1. A structural unit comprising a plurality of U-shaped stirrups and longitudinal rods secured thereto and spacing them apart, some of the stirrups comprising two similar members with intermediate portions in contact and secured together, each having an extremity beyond the secured portion forming a supporting leg, and the two members extending oppositely providing a leg at each side of the unit.
- 30 2. A stirrup element open at the top for a structural unit, comprising two similar members spaced apart at the top and each having a bent lower extremity and a common contact portion along which they are secured together forming a

double bottom portion with the bent extremities at the ends forming supporting legs.

3. A stirrup element for a structural unit open at the top, comprising a pair of Z-shaped bars placed oppositely together and having parallel portions in contact to form a double bottom along which they are secured together, with one extremity of each bar projecting beyond the contacting portion to provide a supporting leg.

4. A structural unit reinforcing element closed at the bottom and open at the top comprising a pair of similar bars having bent ends placed oppositely against each other to form a double bottom upon which they are secured together to form a rigid unit with extremities projecting beyond the bottom portion to provide a supporting leg at each side of the element.

5. A structural U-shaped reinforcing stirrup composed of two bars each bent oppositely at the ends and having two portions substantially at right angles to each other, the bars being turned oppositely with respect to each other with one of said right angled portions parallel and in contact with the other and secured thereto to provide a double bottom with sides upstanding therefrom and the bent extremities of each bar extending at opposite sides of the unit thus formed at the top and bottom thereof.

6. In a structural unit reinforcing stirrup, a pair of bars each bent substantially at right angles and placed oppositely with respect to each other to form a double bottom with sides upstanding therefrom, the bottom portions being rigidly secured together and the extremities of the ends of each bar being bent oppositely to form a lower leg and an upper spacing extension at opposite sides of the unit.

CHESTER J. O'BRIEN.
